TELEVISION ANTENNA

Ralph R. Williams, Detroit, Mich.

Application September 5, 1952, Serial No. 308,100

6 Claims. (Cl. 250—33.67)

1

This invention relates to short wave antennas or aerials and more particularly to an antenna adapted to be disposed within a building or room and connected to a television receiving set.

It is among the objects of the invention to provide an improved short wave antenna for television and similar receivers which utilizes one of the power wires leading to the associated receiver as a source of broadcast signal energy and also receives broadcast signals directly from the surrounding space and correlates the signals from both sources and feeds the correlated signal into the receiver to provide a receiver operating signal of improved strength and clarity; which can be tuned to exact wave lengths and focused to a selected wave reception path to minimize the television reception phenomena referred to as "ghosts" and "flop-over" caused by the simultaneous reception of direct and reflected signals from the same broadcasting station; which may include one or more selectively usable, loop type antennas for different wave length ranges and includes means for adjustably varying the effective antenna length to more accurately discriminate between different wave lengths in the same range; which is effective in a small sized and light weight form as an inside aerial or antenna, but can be utilized in larger sizes as an outside antenna and in a miniature size as a tuner or selector built directly into a receiving set; and which is simple and durable in construction, economical to manufacture, easy to use, and effective and efficient in operation.

Other objects and advantages will become apparent from a consideration of the following description and the appended claims in conjunction with the accompanying drawings wherein:

Figure 1 is a top plan view of a short wave antenna illustrative of the invention with a portion of the top of the housing thereof broken away to more clearly illustrate the construction;

Figure 2 is a cross sectional view on the line 2—2 of Figure 1;

Figure 3 is a cross sectional view on the line 3—3 of Figure 1;

Figure 4 is a cross sectional view on the line 4—4 of Figure 2; and

Figure 5 is a wiring diagram of the antenna.

With continued reference to the drawings, the numeral 10 generally indicates an outer housing of the antenna which housing is formed of electrically insulative material and is illustrated as being of rectangular shape having spaced apart and substantially parallel top and bottom walls 11 and 12, spaced apart and substantially par-

allel end walls 13 and 14 marginally joined to the top and bottom walls along the corresponding edges of the latter and spaced apart and substantially parallel side walls 15 and 16 marginally joined along their side edges to the corresponding edges of the top and bottom walls and joined at their ends to the corresponding ends of the end walls 13 and 14.

The bottom wall 12 constitutes a base for the antenna and carries on its upper surface a bearing plate 17 having a bearing aperture 18 therein.

A cylindrical drum, generally indicated at 20, is mounted on the base 12 for rotational movements of adjustment about its longitudinal center line as an axis and this drum comprises a cylindrical side wall 21 of electrically insulative material and end walls 22 and 23 also of electrically insulative material secured in the side wall 21, one at each end of the latter. The drum is of hollow construction and, while the dimensions of the drum may be varied for different operating conditions without in any way exceeding the scope of the invention, a drum having an outside diameter of approximately two and three-quarter inches, a length of approximately two inches and a wall thickness of approximately one-eighth inch has been found to give excellent results when the device is used as an inside antenna for a television receiver.

The top and bottom walls 22 and 23 of the drum are provided with central apertures and a shaft 24 extends through these apertures and has annular shoulders at the inner sides of the top and bottom walls of the drum. If desired, suitable washers 25 and 26 may be disposed around the shaft between the top and bottom end walls of the drum and the adjacent annular shoulders on the shaft and the drum may be held in position on the shaft by suitable means, such as the nuts 27 and 28 threaded onto the shaft at the outer sides of the end walls of the drum. If desired, washers 29 and 30 may be disposed between the nuts 27 and 28 respectively, and the outer sides of the corresponding top and bottom end walls of the drum and the portion of the shaft 24 below the nut 28 is reduced in diameter to provide a bearing arbor and is received in the aperture 18 in the bearing plate 17. A suitable thrust bearing is provided for the shaft 24 and this may comprise a bearing plate 31 embedded in the bottom wall 12 of the housing at the lower end of the aperture 18 and upon which the bottom end of the shaft 24 rests. At its upper end the shaft 24 is also reduced in diameter to provide an arbor extending through

an aperture 32 in the top wall 11 of the housing and a turning knob 33 is mounted on the upper end of the shaft 24 above the upper surface of the housing top wall 14, so that the drum 20 can be manually rotated about the axis of the shaft 24 for a purpose to be presently described.

One or more loop type antennas are mounted on the drum 20 and these antennas are of relatively different lengths to cover different selected wave length ranges of broadcast signals.

In the arrangement illustrated there are two antennas as generally indicated at 35 and 36 of which the antenna 35 is longer than the antenna 36. Both of the antennas comprise elongated ribbons or wires of flexible, electrically conductive material, such as sheet copper, wound in spiral fashion around the side wall 21 of the drum, each antenna comprising a plurality of loops each of which extends over the opposite ends of the side wall 21 and along the inner and outer sides thereof. The loops are spaced apart a distance no greater than the width of the ribbon and are wound onto the side wall of the drum before the end walls are secured in place in the corresponding ends of the side wall. The longer antenna 35, when wound on a drum of the dimensions indicated above, should comprise a length of wire or ribbon at least ten feet long for television channels and the shorter antenna 36 may comprise a length of ribbon or wire approximately five feet long and has its ends spaced sufficiently from the ends of the antenna 35, so that no interference is set up between the two antennas.

A pair of arcuately curved commutator bars 37 and 38 are disposed against the under side of the bottom end wall 23 of the drum concentric with the axis of the shaft 24 and spaced from each other and these commutator bars have an angular extent substantially the same as the angular extent of the antenna 35 around the drum. Two similar commutator bars 39 and 40 are also mounted on the bottom surface of the bottom end wall 23 of the drum concentric with the axis of the shaft 24 and in spaced apart relationship to each other and these bars have an angular extent coincident with the angular extent of the shorter antenna 36.

Commutator brushes 41 and 42 in the form of thin strips of resilient metal are mounted on the bearing plate 17 and extend outwardly of the cylindrical surface of the drum 20 toward the end wall 13 of the housing 10. These brushes extend one from the inner and one from the outer commutator bar outwardly of the drum 20 and antenna lead-in wires 43 and 44 are connected one to each of these brushes.

A partly cylindrical shield 45 of electrically conductive and preferably magnetic material extends around a portion of the drum 20 in spaced relationship to the outer surface of the side wall of the drum. The shield 45 has an angular extent at least as great as the angular extent of the longer antenna 35 around the drum and has a width substantially as great as the length of the drum. This shield may be firmly mounted on the base 12 by means of a semicircularly curved bar 46 of insulating material of rectangular cross sectional shape, secured on the upper surface of the base 12 and having in its upper surface a longitudinally extending groove 47 which receives the lower edge of the shield 45 which shield is of elongated, rectangular cross sectional shape. While the shield is illustrated as disposed outside the drum, it is to be understood

that it may be disposed inside the drum or that two shields, one disposed outside and the other disposed inside the drum may be used, without in any way exceeding the scope of the invention.

The brushes 41 and 42 have on their inner ends upwardly curved portions 48 and 49 which contact the under sides of the commutator bars and are so located relative to the ends of the shield 45 that when one end of either of the antennas, for example, the antenna 35, begins to move past one end of the shield 45 with the remainder of the antenna disposed outside of the shield, the brushes will engage the corresponding ends of the bars 37 and 38 and the brushes will remain in contact with the commutator bars until the entire antenna is disposed within the angular extent of the shield. However, when the antenna starts out of the angular extent of the shield in the same direction of rotation, the brushes will leave the commutator bars and the antenna will no longer be connected into the circuit. Obviously, the angular extent of the antenna disposed within the angular extent of the shield 35 can be adjusted by rotating the drum 20 backwardly or forwardly with the brushes in engagement with the commutator bars 37 and 38, so that either one loop or all of the loops of the antenna may be disposed within the angular extent of the shield with the brushes in contact with the corresponding commutator bars.

The antenna 35 is connected at one end to the commutator bar 37 by a conductor 50, as illustrated in Figure 5, and at its other end to the commutator bar 38 by a conductor 51. The antenna 36 is correspondingly connected at its opposite ends to the commutator bars 39 and 40 by conductors 52 and 53.

A terminal block 55 is mounted on the upper surface of the base 12 at the corner between the side wall 16 and the end wall 13 and carries three terminal screws 56, 57 and 58 spaced apart longitudinally of the terminal block. A condenser 60 is mounted on the base 12 at a location spaced from the terminal block 55 and has two separate terminals 61 and 62 and a variable resistor 63 is mounted on the base at a location spaced from the condenser 60 and has separate terminals 64 and 65 and an adjusting knob or screw 66. For use as a television receiver antenna the condenser may have a value of approximately three hundred M. M. F. D. and the resistor may have a value of approximately fifty thousand ohms.

A conductor 68 is connected at one end to the terminal screw 56 and at its other end to the ungrounded wire of the two-wire extension cord which supplies electric energy to the associated receiver. This wire may be connected at its other end to the receiver terminal to which the corresponding power wire is connected and lead from the receiver terminal to the antenna terminal 56. The antenna terminal 56 is connected by a conductor 69 to the terminal 61 of the condenser 60 and the terminal 62 of the condenser 60 is connected by a conductor 70 to the terminal 61 of the resistor 63.

The condenser 60 blocks the alternating current from the electric power wire from reaching the resistor 63 while permitting short wave wireless signals on the power wire to reach the resistor. The other terminal 65 of the resistor is connected through a conductor 71 to the antenna lead-in wire 43 leading from the brush 41 to the receiving set and the magnetic shield 45

is also connected at one end to the lead-in wire 43 by a conductor 72. The lead-in wire 43 from the brush 41 leads to the terminal screw 57 and the lead-in wire 44 from the brush 42 leads to the terminal screw 58. From the terminal screws 57 and 58 the lead-in wires are continued to the associated receiver, as indicated at 73 and 74.

With the above described arrangement, short wave signals carried on the power wire 68 will be led to the antenna lead-in wire 43 through the condenser 60 and variable resistor 63 and will also be led to the magnetic shield 45 and to one end of the antenna 35 or 36 the commutator bars of which are in contact with the brushes 41 and 42 at the time. Simultaneously signals will be picked up directly by the operative antenna, the other end of which is connected to the lead-in wire 44 through the brush 42 and the signals received from the various sources will be inductively correlated by the antenna and magnetic shield and fed to the associated receiver as a correlated signal of improved strength and clarity.

It has been found that in large buildings where it is not practical to provide outside aerials or antennas for television receivers in the building and where, consequently, inside antennas must be relied upon, that the broadcast signal situation in any room of such a building is usually highly complicated because of the transmission of the signals along conductive portions of the building structure, the plumbing conduits and the electric wiring and the reflection of the signals from various objects in the building or even in the room itself and from nearby structures. Experimental use with the portable antenna of the present invention has shown that even in a room in which there is such a complicated signal condition as that discussed above, the antenna of this invention can be adjusted to select a single strong signal free of out-of-phase signals in the same or any other channel and that it will receive different wave length signals from different directions with equal facility.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. An antenna assembly for a short wave receiver comprising a base, a hollow cylindrical drum of electrically insulative material, means mounting said drum on said base for rotational movements of adjustment of said drum about its longitudinal center line as an axis, at least one antenna on said drum comprising a partly cylindrical winding of a strand of electrically conductive material wound around the wall of said drum from one end to the other of said drum and having a length corresponding to a predetermined portion of a selected wave length, arcuately shaped commutator bars mounted on one end of said drums concentric with the axis of rotation of the drum in spaced apart relationship to each other and connected one to one end and one to the other end of said antenna, brushes respectively engaging said commutator bars, lead-in wires extending one from each of

said brushes for connection to an associated receiver, a partly cylindrical shield of electrically conductive magnetic material extending partly around said drum and spaced therefrom, a condenser having separate terminals, a conductor extending from one condenser terminal for connection to an electric power wire, a variable resistor having separate terminals, a conductor connecting one of said resistor terminals with the other of said condenser terminals, and conductor means connecting the other resistor terminal with said shield and with one of said lead-in wires.

2. A short wave antenna assembly comprising a base, a hollow support of cylindrical shape and of electrically insulative material disposed above said base, means mounting said support on said base for rotational movements of adjustment about said longitudinal center line as an axis, at least one antenna winding of electrically conductive material spirally wound on said cylindrical support over the ends and along the inner and outer sides of said support, a pair of lead-in wires extending from said base for connecting the antenna assembly to an associated receiver, means connecting said lead-in wires one to each end of said antenna winding, a shield of electrically conductive material and of partly cylindrical shape fixedly mounted along one curved edge thereof on said base and extending partly around said support in spaced relationship thereto, conductor means connecting said shield to one of said lead-in wires, a condenser and a resistor connected together in a series, said resistor being connected directly to said one lead-in wire, and a conductor extending from said condenser for connecting the latter to an electric power wire.

3. A short wave antenna assembly comprising a base, a hollow support of cylindrical shape and of electrically insulative material disposed above said base, means mounting said support on said base for rotational movements of adjustment about said longitudinal center line as an axis, at least one antenna winding of electrically conductive material spirally wound on said cylindrical support over the ends and along the inner and outer sides of said support, a pair of lead-in wires extending from said base for connecting the antenna assembly to an associated receiver, means connecting said lead-in wires one to each end of said antenna winding, a shield of electrically conductive material and of partly cylindrical shape fixedly mounted along one curved edge thereof on said base and extending partly around said support in spaced relationship thereto, conductor means connecting said shield to one of said lead-in wires, a condenser and a resistor connected together in series, said resistor being connected directly to said one lead-in wire, and a conductor extending from said condenser for connecting the latter to an electric power line, said shield being of elongated rectangular cross sectional shape and having a width between its curved edges substantially equal to the length of said support and a length such that it extends around said support to an angular extent substantially equal to the angular extent to which the longest antenna winding on said support extends around the support.

4. A short wave antenna assembly comprising a base, a hollow support of cylindrical shape and of electrically insulative material disposed above said base, means mounting said support on said base for rotational movements of adjustment

about its longitudinal center line as an axis, antenna windings of electrically conductive material spirally wound on said cylindrical support over the ends and along the inner and outer sides of said support in spaced relationship to each other and extending to respectively different angular extents around said support, a pair of lead-in wires extending from said base for connecting the antenna assembly to an associated receiver, means selectively connecting said lead-in wires to said antenna windings one to each end of the selected winding in accordance with the rotational position of adjustment of said support, a shield of electrically conductive material and of partly cylindrical shape fixedly mounted along one curved edge thereof on said base and extending partly around said support in spaced relationship thereto, conductor means connecting said shield to one of said lead-in wires, a condenser and a resistor connected in series, said resistor being connected directly to said one lead-in wire, and a conductor extending from said condenser for connecting the latter to an electric power wire, said shield being of elongated rectangular cross sectional shape and having a width between its curved edges substantially equal to the length of said support and a length such that it extends around the support to an angular extent substantially equal to the angular extent at which the longest antenna winding on said support extends around the support.

5. A short wave antenna assembly comprising a base, a hollow support of cylindrical shape and of electrically insulative material disposed above said base, means mounting said support on said base for rotational movements of adjustment about its longitudinal center line as an axis, antenna windings of electrically conductive material spirally wound on said cylindrical support over the ends and along the inner and outer sides of said support in spaced relationship to each other and extending to respectively different angular extents around said support, a pair of lead-in wires extending from said base for connecting the antenna assembly to an associated receiver, means selectively connecting said lead-in wires to said antenna windings one to each end of the selected winding in accordance with the rotational position of adjustment of said support, a shield of electrically conductive material and of partly cylindrical shape fixedly mounted along one curved edge thereof on said base and extending partly around said support in spaced relationship thereto, conductor means connect-

ing said shield to one of said lead-in wires, a condenser and a resistor connected in series, said resistor being connected directly to said one lead-in wire, and a conductor extending from said condenser for connecting the latter to an electric power wire, said shield being of elongated rectangular cross sectional shape and having a width between its curved edges substantially equal to the length of said support and a length such that it extends around the support to an angular extent substantially equal to the angular extent at which the longest antenna winding on said support extends around the support and said antenna assembly being freely portable and movable from place to place within the limits of the length of said lead-in wires while connected to an associated receiver.

6. An antenna assembly for a short wave receiver comprising a base, and antenna winding of a shape to constitute a portion of the wall of a hollow cylinder, means supporting said antenna winding on said base for rotational movements of adjustment of the winding about the axis of the complete hollow cylinder of which the shape of said winding constitutes a portion, lead-in wires connected one to each end of said antenna winding for connecting the winding to an associated receiver, a shield of electrically conductive material and of partly cylindrical shape fixedly mounted on said base and spaced from the outer surface of the cylinder of which the shape of said antenna winding constitutes a portion, means electrically connecting said shield with one of said lead-in wires, a resistor and a condenser connected in series with said one lead-in wire, and conductor means connected to said condenser for connecting the latter to an elongated electrical conductor which constitutes a component of a building.
